Des. 211,060
Patented May 14, 1968

211,060

COMBINED MOVING PICTURE CAMERA, PROJECTOR AND SUPPORTING BASE THEREFOR OR SIMILAR ARTICLE

Tetsuo Takata and Shigekazu Inamoto, Tokyo, Japan, as
signors, by mesne assignments, to Suzuei Sangyo Co.,
Ltd., Tokyo, Japan, a corporation of Japan

Filed Dec. 14, 1966, Ser. No. 5,042

Term of patent 14 years

Claims priority, application Japan Oct. 24, 1966

(Cl. D61—1)

Fig. 1

Fig. 2

Fig. 3

Fig. 4

Fig. 5

Fig. 6

Fig. 7

Fig. 8

FIGURE 1 is a front elevation of a combined moving picture camera, projector and supporting base therefor or similar article, showing our new design;

FIG. 2 is a rear elevation thereof;

FIG. 3 is a left end view thereof;

FIG. 4 is a right end view thereof;

FIG. 4 is a top plan view thereof;

FIG. 5 is a top plan view thereof;

FIG. 6 is a bottom plan view thereof;

FIG. 7 is a front elevation thereof, the camera being turned for 90°; and

FIG. 8 is a top plan view thereof in the position shown in FIG. 7.

We claim:

The ornamental design for a combined moving picture camera, projector and supporting base therefor or similar article, as shown.
